UNITED STATES PATENT OFFICE.

ROBERT SCHORR, OF WÜRTEMBERG, GERMANY.

METHOD OF PRODUCING COLORED IMPRESSIONS.

SPECIFICATION forming part of Letters Patent No. 446,004, dated February 10, 1891.

Application filed September 18, 1889. Serial No. 324,345. (No specimens.)

To all whom it may concern:

Be it known that I, ROBERT SCHORR, a resident of Schwäbisch-Hall, Würtemberg, Germany, have invented an Improvement in the Method of Producing Colored Impressions, of which the following is a specification.

The object of my method is to produce colored impressions by photography and to do away with the inaccuracies which now occur in the lithographic process.

My method consists, briefly stated, of photographing the picture to be printed and developing the negatives thereof to different intensities, according to the strength of the color to be employed in the printing, and transferring such colored impressions upon the stone or zinc plate by the usual method of points.

10 The method of multiplying pictures now in use for lithographic work is to employ a lithographer to make a water-color drawing of the picture to be printed, and then to transfer the picture disintegrated into separate 15 colors upon lithographic stones for printing purposes. The disadvantage of this system is that there are often very gross mistakes in such reproductions, owing to the inaccuracies 20 of execution of the lithographer.

25 By my method I take a number of photographs of the picture to be produced and develop the negatives to different intensities 30 by length of exposure to the light. These negatives of different intensities, which are 35 to form the basis for the color-plates, are so developed that they can be adapted to a stronger or fainter color, as the case demands. From the above-described negatives as many photographs on glass are taken 40 as there are color-plates required for the picture. These photographs are called "dia- 45 positives," as they appear positive on the opposite side of the glass negative. These dia- positives are now retouched by means of a brush or pencil corresponding to the single 50 colors employed in the reproduction of the picture and corresponding to the plates made by hand by the lithographers. The next step is to transfer these plates to the stones 55 or zinc plates; but as they are negatives—that is, what is white in the picture would appear black on the stones—a direct transfer cannot be performed. To avoid this dif-

60 ficulty I rephotograph the dia-positive color- 65 plates, and thus produce negatives which 55 can be transferred upon the stone or zinc 60 plates by any of the usual modes of trans- 70 ferring such negatives, as by means of points, 75 which consists in placing between the nega- 80 tive and the stone or zinc plate, which is cov- 85 ered with a sensitive coating of chrome, a 90 thin membrane of gelatine uniformly perfo- 95 rated with points and lines, and exposing 100 the same to the light, whereupon the picture 105 on the negative appears in dots and lines 110 upon the stone (photolithograph) or upon 115 the zinc plate (autotype) and is ready to be 120 etched. The etched stone or zinc plate is 125 supplied with color by means of a roller, 130 such color being rolled in, and is now ready 135 for printing. By printing the different colors 140 upon each other the reproduction of the 145 picture in its natural colors is produced.

The advantages of my method are to mul- 15 tiply the production of pictures by the pro- 16 cess of lithography or book-printing without 17 employing a lithographer, thus eliminating 18 any possible error and producing an exact 19 representation by photography. Further, 20 my method can be employed either in lithog- 21 raphy or by the aid of zinc plates.

Therefore, having described my invention, 22 what I claim is—

The herein-described method of producing 23 a multiplication of pictures in their original 24 colors by lithography or book-printing, which 25 consists in photographing the picture, pro- 26 ducing therefrom a series of negatives of va- 27 rying intensity, then producing from these 28 negatives by photography a series of dia- 29 positives of varying intensities, (upon glass,) then 30 touching up the said dia-positives with the 31 color corresponding to the intensity of the 32 plate, then reducing the dia-positives to nega- 33 tives by photography, and finally transfer- 34 ring the same upon the lithographic stone or 35 zinc plate and printing one color upon an- 36 other until the picture is produced in colors, 37 substantially as and for the purposes set forth.

The foregoing specification of my inven- 38 tion signed by me this 2d day of September, 39 1889.

ROBERT SCHORR.
